UNITED STATES PATENT OFFICE.

JOHN THOMAS, OF CEDAR RAPIDS, IOWA.

TRACE-CARRIER.

SPECIFICATION forming part of Letters Patent No. 249,692, dated November 15, 1881.

Application filed June 6, 1881. (Model.)

To all whom it may concern:

Be it known that I, JOHN THOMAS, of Cedar Rapids, in the county of Linn and State of Iowa, have invented a new Improvement in 5 Trace-Carriers; and I do hereby declare the following, when taken in connection with the accompanying drawings and the letters of reference marked thereon, to be a full, clear, and exact description of the same, and which said 10 drawings constitute part of this specification, and represent, in—

15 This invention relates to an improvement in the article of saddlery hardware known to the trade as "trace-carriers"—that is to say, a device to be attached to the harness at the intersection of the back and hip straps, to which 20 the cockeye of the trace may be hooked when detached from the whiffletree, the object being, principally, to arrange the hooks in rear of the hip-straps, whereby the usual bridge over those straps, and to which the hooks are at- 25 tached, is avoided; and it consists in the construction, as hereinafter described, and particu- larly recited in the claims.

The frame is in the form of a parallelogram, the forward end or loop, A, to receive the back- 30 strap; the two sides B B, near the forward end, to receive the hip-straps; the rear end or loop, C, for the crupper-strap. At each side and at the rear a diagonal projection is made from the frame of the two sides D D, con- 35 nected at their outer ends by a bar, E. These parts are all in the same plane, and the dia- 40 gonal frame sufficiently far to the rear of the forward end, A, to permit the hip-straps to be at- tached to the sides B forward of the dia- 45 gonal parts D.

Upon each of the cross-bars or ends E of the diagonal parts of the frame a hook, F, is formed, turning upward, inward, and downward, as seen in Figs. 2 and 3. These hooks F are fit- 45 ted for engaging the cockeyes. Their points extend downward nearly to the plane of the bottom of the frame. Upon the inside of the frame, and at the point where the diagonal sides D intersect with the sides B, a connec- 50 tion is made across the frame turning inward and upward, appearing like a semicircular inner end of the diagonal parts of the frame, the

said semicircular ends joined where they meet above the plane of the frame and so as to form a guard for the hooks. This completes the 55 holder. It is arranged upon a leather "chafe," the straps attached in the usual manner.

The ends of the hooks stand nearly down to the chafe; but in attaching the cockeyes the chafe will yield or the plate rise slightly there- 60 from, so as to permit the cockeyes to enter be- tween the chafe and the end of the hook, and then the chafe itself prevents accidental de- tachment. The guard formed by the intersec- 65 tion of the semicircular parts, as at G, prevents the reins from catching beneath the hooks or the hooks interfering with the reins.

I do not broadly claim a trace-carrier con- 70 structed for attachment to the harness at the junction of the back and hip straps; neither do I broadly claim a frame constructed for at- 75 tachment to the back and hip straps provided with hooks to engage the cockeyes of the traces; ne'ther do I claim such a trace-carrier provided with a guard to prevent the reins from engaging the hooks, as such I am aware 80 is not new; but

What I do claim is—

1. The herein-described trace-carrier, con- 80 sisting of the frame in the form of a parallelo- gram composed of the end loops, A C, and two sides, B B, with the diagonal parts D intersecting said sides B at their rear parts, each of said diagonal parts constructed with a hook on its outer portion turning upward, inward, 85 and downward in a vertical plane parallel with the said diagonal parts, substantially as de- scribed.

2. The herein-described trace-carrier, con- 90 sisting of the frame in the form of a parallelo- gram composed of the ends A C and two sides, B B, with the diagonal parts D intersecting said sides B at the rear part of said sides, each of said diagonal parts constructed with a hook on its outer end turning upward, inward, and 95 downward in a vertical plane parallel with the said diagonal parts, with the guard G extend- ing from the sides of the frame inward and upward between the hooks, substantially as de- scribed.

JOHN THOMAS.
